Assistant Examiner — Maheen Khurshid

(57) **CLAIM**

The ornamental design for an insert for a breast pump as shown and described.

DESCRIPTION

FIG. 1 is a rear perspective view of a first embodiment of an insert for a breast pump showing our new design;

FIG. 2 is a front perspective view thereof;

FIG. 3 is a bottom side view thereof;

FIG. 4 is a top side view thereof;

FIG. 5 is a right side view thereof;

FIG. 6 is a left side view thereof;

FIG. 7 is a top side view thereof;

FIG. 8 is a bottom side view thereof;

FIG. 9 is a rear perspective view of a second embodiment of an insert for a breast pump showing our new design;

FIG. 10 is a front perspective view thereof;

FIG. 11 is a bottom side view thereof;

FIG. 12 is a top side view thereof;

FIG. 13 is a right side view thereof;

FIG. 14 is a left side view thereof;

FIG. 15 is a top side view thereof;

FIG. 16 is a bottom side view thereof;

FIG. 17 is a rear perspective view of a third embodiment of an insert for a breast pump showing our new design;

FIG. 18 is a front perspective view thereof;

FIG. 19 is a bottom side view thereof;

FIG. 20 is a top side view thereof;

FIG. 21 is a right side view thereof;

FIG. 22 is a left side view thereof;

FIG. 23 is a top side view thereof; and,

FIG. 24 is a bottom side view thereof.

The broken lines depict portions of the insert for a breast pump that form no part of the claimed design.
